Specification for Design.

Patented Feb. 8, 1921.

Application filed April 22, 1919. Serial No. 291,988. Term of patent 3½ years.

To all whom it may concern:

Be it known that I, WALTER L. FOX, a citizen of the United States, residing at Brooklyn, in the county of Kings and State of New York, have invented a new, original, and ornamental Design for Desks, of which the following is a specification.

Reference is had to the accompanying drawing in which:

The figure is a view in perspective of a desk showing my new design.

I claim:

The ornamental design for a desk, as shown.

In testimony whereof I affix my signature in presence of a witness.

WALTER L. FOX.
